UNITED STATES PATENT OFFICE.

WALLACE METTS, OF STOUGHTON, MASSACHUSETTS, ASSIGNOR TO KINGMAN MANUFACTURING COMPANY, OF STOUGHTON, MASSACHUSETTS, A CORPORATION OF MASSACHUSETTS.

DESIGN FOR A GAITER.

58,799.

Specification for Design.

Patented Aug. 30, 1921.

Application filed March 28, 1921. Serial No. 456,486. Term of patent 7 years.

To all whom it may concern:

Be it known that I, WALLACE METTS, a citizen of the United States, residing at Stoughton, in the county of Norfolk and State of Massachusetts, have invented a new, original, and ornamental Design for Gaiters, of which the following is a specification, reference being had to the accompanying drawing, forming part hereof.

The essence of my design consists of the

provision of deep cuttings, whereby sections are removed from the front of the leg portion of the gaiter, to below the instep; leaving only narrow transversely extending sections composing this part of the front.

I claim:

The ornamental design for a gaiter, as shown and described.

WALLACE METTS.
